CLAIM

We claim the ornamental design for a razor component, as shown and described.

DESCRIPTION

FIG. 1 is a front perspective view of a razor component of the present invention;

FIG. 2 is a front view of the razor component of FIG. 1;
FIG. 3 is a back view of the razor component of FIG. 1;
FIG. 4 is a right side view of the razor component of FIG. 1;

FIG. 5 is a left side view of the razor component of FIG. 1;
FIG. 6 is a bottom view of the razor component of FIG. 1;
and,
FIG. 7 is a rear perspective of a razor component of FIG. 1.
